UNITED STATES PATENT OFFICE.

THOMAS E. MURRAY, JR., OF BROOKLYN, NEW YORK.

RADIATOR.

Application filed February 17, 1927. Serial No. 188,870.

In a certain previous application No. 709, 080, filed April 26, 1924, I have described a type of radiator with a steam pipe or similar heating element to which are applied corrugated plates forming an extended radiating surface which conducts the heat rapidly to the surrounding air and which form flues inducing a rapid circulation of the heated air; and this principle is embodied in several other pending applications of mine.

The present invention aims to provide certain improvements in radiators working on similar principles.

Fig. 1 is a perspective view of a complete radiator;

Figs. 2, 3, 4 and 5 are similar, partial, views of modifications;

Fig. 6 is a transverse vertical section of Fig. 5;

Figs. 7 and 8 are end elevations of arrangements employing two kinds of heating element;

Fig. 9 is a perspective view of one of the plates or fins of Fig. 7;

Fig. 10 is a transverse horizontal section of part of the radiator of Figs. 7 and 9;

Fig. 11 is a perspective view illustrating a further modification.

Fig. 12 is a section similar to Fig. 10 illustrating a modification.

Fig. 13 is a section similar to Fig. 7, also illustrating a modification.

In Figs. 1 to 6 the heating element is assumed to consist of one or more lengths of steam pipe 1 extending substantially horizontally, connected to each other at alternate ends to form a single conduit; or they may be connected in parallel to headers at opposite ends. To these are bonded or secured

transversely extending plates or fins 2 which provide an extended radiating surface. These are distinguished from the radiating structure of my previous application No. 709,080 in that they are separate plates instead of parts of a corrugated structure extending continuously lengthwise. Preferably the structure is enclosed in a casing, and this may be of various styles.

According to Fig. 1, there is a front plate 3 which may be paneled and finished in any decorative scheme. The back is encased by a similar plate 4, flanged to provide end plates 5. The front and back plates close the spaces between the radiating plates and thus form closed vertical flues (closed in cross-section) which facilitate and acceler-

ate the circulation, so as to adapt the radiator for use with high temperature heating mediums and to secure the quick and efficient heating of a room.

According to Fig. 2 a casing is used which includes a front plate 3 and end plates 6 in one piece adapted to be applied after the radiator is set up, the end plates having notches 7 which are so located as to pass obliquely downward over the projecting ends of the heating element or elements, and hold the casing in place. In this construction, the back of the radiator is left open.

The back may be closed by a single plate 70 corresponding to the front plate. Or each flue may be closed separately by providing flanges 8, Fig. 3, on the rear edges of the fins 2. Or separate flanged strips 9 (Fig. 4) may be inserted between the several fins 75 2 with flanges 10 soldered or otherwise fastened to the outer edge portions of the fins. Similar flue-closing plates or strips of other designs and mounted in other ways may be used. And the flue-closing plates or strips of Figs. 3 and 4 may be used at the front as well as the back.

Where it is not desired to have the top of the casing open a covering top plate 11, Fig. 5, may be used, located somewhat above 85 the radiating structure and the casing may be provided at the front with a grating 12. In this case a back plate 13, Fig. 6, should be used with a forwardly curved deflector 14 for directing the ascending hot air forward 90 through the grating 12 as shown by the arrows. A similar grating may be laid horizontally across the top of Figs. 1 to 4 to guard and conceal the top edges of the fins 4.

The arrangements described above may be applied with fins of various shapes and with various styles and combinations of heating elements. Fig. 7 shows a fin 14 of different proportions, with heating elements arranged horizontally alongside of one another so as to make the radiator of comparatively small height. The heating elements in this case are circular steam pipes 15 and between them a rectangular electric heating element 16. 105 Fig. 8 is similar except that the steam pipes 17 are tapered at the bottom so that any water collecting there will have considerable depth in proportion to its volume and a diminished frictional resistance to flow 110 compared with a broader section of the same volume. The electrical heating element 18

in this figure is of circular shape. Various other modifications may be adopted for each of the heating elements.

Figs. 9 and 10 show how the plates or fins 6 are mounted on the heating elements. The plates 14 are drawn out and the ends cut off to leave circular flanges 19 and rectangular flanges 20 which fit closely on the heating elements. These are then soldered, brazed or 10 welded on to the heating elements or otherwise secured closely to the outside of the latter to effect a good heat-conducting contact. For example each plate 14 may be made in two parts brought together along edges indicated by the dotted line 21 and pressed 15 against the heating elements while the solder is heated. Or each plate 14 may be in one piece fitting on the heating elements. The flanges 19 and 20 may be made long 20 enough to serve also as spacers, the edges of the flanges of one plate engaging the back of the next plate for example as in Fig. 10.

The radiator may be equally used for 25 cooling air by circulating cold brine or the like through the pipes so that the latter become a heating element only in the negative sense, that is, they extract heat from the radiating structure and induce a flow of the cool air downward through the flues similar 30 to the upward circulation of air induced by the passage of steam through the pipes.

Fig. 11 shows an alternative method of fastening a fin to a heating element which may be adapted to any of the previously 35 described constructions. This figure also shows a fin 22 applied to only one side of the heating element. The fin is flanged to provide a socket 23 with flanges 24 above and below. The heating element 15 is held in 40 place by a strap having a socket 25 and flanges 26 above and below. The parts are clamped together and secured by spot welds 27 through the flanges. A continuous strap may be employed extending over all or 45 several successive fins along the length of the heating element; or a separate strap may be used for each fin. This mode of connection has an advantage, where the heating element and the fins are of metals having different 50 coefficients of expansion, in permitting a slight relative movement between the two. Other methods of fastening the strap may be used, and the fastening means may be supplemented by soldering, brazing or welding 55 to the heating element where relative movement is not necessary.

In any case where soldered joints are used they should be fairly close together along the heating element to avoid melting the 60 solder, particularly when using high temperature heating elements.

Various metals may be used for the steam pipe and the casing of the electric heating element and for the fins. The greatest efficiency 65 is secured by making all these parts

of copper. But steel or iron may be used with good effect. Or, for economy's sake fins, constituting the greater quantity of metal in the structure, may be made of steel and the heating elements of copper.

Fig. 12 illustrates a way of providing closed vertical flues similar to those referred to in Figs. 3 and 4. The plates 14 in this case are secured on the heating elements 15 and 16 in any of the ways above described. At their outer vertical edges the plates have flanges 28 which close the space between them so as to convert such spaces into closed flues.

According to Fig. 13, the steam or hot 80 water is carried in a vertically elongated vessel 29 tapering toward the top. The radiating plates 30 are correspondingly high and narrow. Electric heating elements 16, like those in Fig. 7, are combined with the 85 steam or hot water heating element in one radiator. Such electric heating elements may be used in various locations and combinations, one at the bottom, one at either side of the vessel 39 or one at the top, or 90 the combination of four of these as illustrated.

These heating elements 16 are preferably of the type illustrated in the Wiegand Patent No. 1,614,938 of January 18, 1927 95 having a resistor carried in a body of refractory insulating material enveloped in a long thin metal sheath. Such strip heaters attain very high temperatures, sometimes above red hot, in use, and would be dangerous for domestic heating. But they are peculiarly adapted to use with the extended surface radiator described. Such a radiating structure removes the heat from the heating element so rapidly that exposed 100 parts of the radiator are sufficiently cool to be quite safe.

No claim is made herein for the casings shown, these being the invention of Irving T. Bennett and covered in a separate application of his for patent, Serial No. 233,594, filed November 16th, 1927.

Various other modifications may be made by those skilled in the art without departing from the invention as defined in the 115 following claims.

What I claim is:—

1. A radiator comprising a long narrow heating element extending horizontally, separate transverse fins secured thereto having substantially vertical outer edges and means for closing the spaces between said edges of each pair of adjacent fins to form between them vertical flues entirely closed in horizontal section for inducing a rapid circulation of the heated air.

2. A radiator comprising a plurality of long narrow heating elements extending horizontally and offset horizontally from each other, transverse fins secured to said

heating elements and having substantially vertical outer edges and means for closing the spaces between said edges of adjacent plates to form between them vertical flues entirely closed in horizontal section for inducing a rapid circulation of the heated air.

3. The radiator of claim 2, one of said heating elements being a pipe and another being an electric heating device.

4. A radiator comprising an electric heating element of the strip type extending hori-

zontally, adapted to attain a very high temperature, transverse fins secured thereto having substantially vertical outer edges and 15 means for closing the spaces between said edges of adjacent fins so as to shield said high temperature, heating element and to form vertical flues entirely closed in cross-section for inducing a rapid circulation of 20 the heated air.

In witness whereof, I have hereunto signed my name.

THOMAS E. MURRAY, JR.
